UNITED STATES PATENT OFFICE.

JOHN M. LANDFAIR, OF BLACK LICK, PENNSYLVANIA.

WINDOW-SCREEN.

1,073,426.

Specification of Letters Patent. Patented Sept. 16, 1913.

Application filed January 15, 1913. Serial No. 742,292.

To all whom it may concern:

Be it known that I, JOHN M. LANDFAIR, a citizen of the United States, residing at Black Lick, in the county of Indiana and State of Pennsylvania, have invented a new and useful Window-Screen, of which the following is a specification.

The present invention relates to improvements in window screens, the primary object of the invention being the provision of an interchangeable screen adapted to be used either upon the lower or upper sash of a window, the same being so constructed that due to the opening or closing of the sash, the screen is stretched or contracted to cover the opening, the same being in unobstructed view when the sash is closed, there being provided further means to permit of the easy detachment of the screen carrying member from the sash so that the sash may be opened or closed without affecting the screen.

A further object of the present invention is the provision of a frame open at one side and bodily carrying a screen roll and means whereby the screen may be wound or unwound due to the movement of the window sash, there being provided means for attachment to the sash to readily disengage or engage the sliding member of the device for actuating the screen roll.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a plan view of a window frame and sashes taken from the inside and equipped with the present invention. Fig. 2 is a similar view taken from the outside. Fig. 3 is a longitudinal sectional view through the frame and sashes, with the present screen device in the position it assumes when the sashes are closed. Fig. 4 is a view in elevation of the screen roller carrying device. Fig. 5 is a perspective view of the removable frame showing the relative position therewith of the screen carrying roll, screen and auxiliary operating

means for rotating the roll. Fig. 6 is a view illustrating the method of attaching the screen to the roll.

Referring to the drawings, the numeral 1 designates the window frame which is provided with the usual lower sash 2 and the upper sash 3, the present device being constructed to be interchangeable for attachment to a window frame and for coöperation with either one of the sashes. As such is the case the description of one of the complete mechanisms will suffice for both.

The two plates 4 are provided for attachment to the opposite sides of the window frame and are provided with the inwardly projecting plates 4', which are of such a thickness as to permit of the passage of one sash past the other without interfering with the proper manipulation of the sashes. Connected across the ends of the plates 4' is the screen carrying plate 5 which is detachably connected to the plates 4' by means of the rivets or bolts 20.

A sliding plate 6 is provided and at its respective ends has attached thereto the plates 7 and the cleats 8, which coact with the extreme ends to fit astride the respective plates 4' and thus provide a guiding means for the sliding plate 6 vertically between the plates 4'. In order that the sliding plate 6 may be detachably connected to either one of the respective sashes 2 and 3 and adjacent to the respective lower and upper rails thereof, two plates 9 are attached to the respective lower and upper rails of the sashes and each is provided with the right angled terminal 10 adapted to engage one edge of the plate 6, as clearly shown in Fig. 5, to cause the plate 6 to be moved toward the connecting and screen carrying plate 5, there being formed in the plate 9, a resilient tongue 11 which provides a means for detachably connecting the plate 6 between the tongue 11 and lug 10 of the plate 9, so that as either one of the sashes is elevated or lowered the plate 6 will be carried by cleats or tongues 11. The cleats 11 may be depressed to permit of the disengagement of the plate 6 from the sash when it is desired to disconnect the window screen from the sash and render the same inoperative when it is desired to wash the windows or open the same without presenting the screen.

The sliding plate 6 is provided with the right angled apertured arms or lugs 12, in which are journaled for rotation the pintles or pins 13 of the metal heads 14, each one of which is provided with the inwardly bent lugs or tangs 15 which engage and embrace the respective ends of the cylinder 16. This cylinder 16, as clearly shown in Fig. 4, is preferably made of a large mesh screen of wire of a heavier gage than the screen 19, said screen 19 as clearly shown having its end 18 secured at 17 to the roller 16. It will thus be seen that as either one of the respective sashes is slid to open position, that the plate 6 will be moved so that the screen 19 will be unwound and thus cover the open space, as clearly shown in Fig. 1 with its side edges resting flush upon the adjacent faces of the plates 4', while in order to provide a means for rotating the roll 16 in the opposite direction when either one of the sashes is closed and consequently roll the screen 19 upon the roll 16, the flat tapes 22, each of approximately the same thickness as the screen 19 have their inner ends connected to one of the lugs 15 as at 21, Fig. 4, while the opposite end is disposed beneath the resilient plate 24 formed from the body of the plate 4', the bent over end 23 being positioned as shown in Fig. 5, to be again engaged by the small auxiliary clamping plate 25, of the plate 24. By this means the tape is readily secured to or detached from its respective plate 4' and any slack may be taken care of due to the positioning of the end 23.

From the foregoing description, taken in connection with the drawings it is evident that with a window screen constructed according to and embodying the present invention, the sliding plate 6 which detachably carries the roller 16 and the screen 19 and the tape 22, is bodily carried by the frame constituting the plates 4 and 5 which are readily attached to the window frames, as shown in Figs. 1, 2 and 3, it simply being necessary to use several screws for engaging the plates 4 with the adjacent sides of the window frame, so that the plates 4 will readily fit between the meeting portions of the sashes and not interfere with the sliding movement of said sashes.

The plates 9 are positioned upon the respective lower and upper rails of the sashes 2 and 3 so that under normal conditions, the resilient tongue or prong 11 will retain the plate 6 in the position, as shown in Fig. 5, so that the plate 6 will be moved with its respective sash and cause the unrolling or rolling of the screen 19, due to the movement of the sash. It is also apparent that when it is desirable to disconnect the plate 6 so that the sash may be opened without unrolling the screen, the resilient tongues or tangs 11 may be depressed and

the metal plate 6 swung outwardly so that when the sash is moved open the plate 6 will remain stationary.

By providing the detachable fastenings 20, the plate 5 with the screen 19 may be removed and as the journaling lugs or arms 12 are resilient, the roll 16 may also be removed, while the connection at 24—25 permits of the ready detachment of the plates 22, thus permitting the screened portions to be removed in the winter time leaving the plates 4 attached to the window frame.

As shown in Fig. 6, the clamping plates 27 and 28, bind the end of the screen 19 to the roller 16, longitudinally of the roller, screws 29 being employed to clamp the plates, the outer one of which is in the same plane as the outer circumference of the roller 16.

What is claimed is:

1. The combination with a window frame and a slidable sash, of a window screen including a frame detachably secured to the window frame and parallel to the sash, a plate slidably mounted upon the detachable frame, a rotatable screen carrying roller carried by said plate, a screen attached to the roller and to the detachable frame, a tape connected to the roller and also to the frame, the tape being wound upon the roller when the screen is unwound and vice versa, and means carried by the sash for detachably engaging the sliding plate to cause the winding and unwinding of the screen as the sash is closed and opened. 100

2. The combination with a window frame and slidable sash, of a window screen, including a frame detachably secured to the window frame and parallel with the sash, a plate slidably mounted transversely of the detachable frame, a rotatable screen carrying roller detachably carried by said plate, a screen attached to the roller and to the detachable frame, a tape connected to the roller and also to the frame, the tape being wound upon the roller when the screen is unwound, and vice versa, and a resilient catch carried by the sash for detachably engaging the sliding plate whereby the plate may be detached from movement with the sash and attached to cause the roller to wind and unwind the screen and tape due to the movement of the sash. 115

3. A rolling screen attachment for window frames and sashes including a bodily removable and attachable U-shaped frame, a sliding roll carrying member disposed adjacent one face and transversely of the terminals of the frame, a screen connected to said roller at one end and having the opposite end connected to the connecting member of the frame, and two tapes, one to each terminal, connected to the respective heads of the roller and each at a point adjacent the end of its terminal of the frame. 130

4. A screen roller attachment for window sashes and frames, including two parallel plates, a bridging member connected across said plates and at right angles to the respective ends thereof, a plate slidably mounted between the two parallel plates for movement to and from the connecting plate, a roller detachably carried by the sliding plate, a screen having one terminal connected to the roller and the opposite terminal to the connecting plate, two tapes, said tapes having one of their respective ends con-
5. A screen roller attachment for window sashes and frames, including two parallel plates, a bridging member connected across said plates and at right angles to the respective ends thereof, a plate slidably mounted between the two parallel plates for movement to and from the connecting plate, a roller detachably carried by the sliding plate, a screen having one terminal connected to the roller and the opposite terminal to the connecting plate, two tapes, said tapes having one of their respective ends con-
10. A screen roller attachment for window sashes and frames, including two parallel plates, a bridging member connected across said plates and at right angles to the respective ends thereof, a plate slidably mounted between the two parallel plates for movement to and from the connecting plate, a roller detachably carried by the sliding plate, a screen having one terminal connected to the roller and the opposite terminal to the connecting plate, two tapes, said tapes having one of their respective ends con-

nected to the heads of the roller, and means for detachably clamping the opposite ends of the tapes to the extreme ends of the parallel plates. 15

In testimony that I claim the foregoing as my own, I have hereto affixed my signature in the presence of two witnesses.

JOHN M. LANDFAIR.
